UNITED STATES PATENT OFFICE.

MARSHMAN W. HAZEN AND OTTO PETERMANN, OF NEW YORK, N. Y., ASSIGNEES, BY
DIRECT AND MESNE ASSIGNMENTS, TO STANDARD TYPEWRITER COMPANY, A
CORPORATION OF NEW YORK.

TYPE-WRITING MACHINE.

1,094,560.

Specification of Letters Patent. Patented Apr. 28, 1914.

Application filed March 27, 1909. Serial No. 486,181.

To all whom it may concern:

Be it known that we, MARSHMAN W. HAZEN and OTTO PETERMANN, citizens of the United States and of the Republic of Switzerland, respectively, and residents of New York, county and State of New York, have invented certain new and useful Improvements in Type-Writing Machines, of which the following is a full, clear, and exact 10 description.

This invention relates more particularly to carriages of front-strike or visible type-writing machines.

One of the principal objects of the invention is to provide a simple and efficient carriage having a main frame member and a supplementary frame member in the latter of which the platen is mounted and so holding the supplementary frame member and platen 20 with relation to the main member that the two may move together lengthwise of the carriage support, and at the same time permit the platen and the supplementary frame member to have a vertical shift movement entirely independent of any movement of the main frame member to adapt the platen to have different adjustments in order that the type-heads may have a plurality of characters thereon.

30 A further object of the invention is to provide simple and efficient ball bearings entirely independent of each other and which are so arranged and constructed that the platen and carriage are supported in a substantial manner, and which adapts the carriage to move lengthwise of its support with very little friction.

With these and other objects in view, the invention will be hereinafter more particularly described with reference to the accompanying drawings which form a part of this specification, and will then be pointed out in the claims at the end of the description.

45 In the drawings, Figure 1 is a rear elevation of one form of machine embodying our invention, showing the escapement and the means for supporting the carriage. Fig. 2 is a longitudinal section, partly in elevation, of the machine. Fig. 3 is a fragmentary vertical section of a part of the escapement mechanism. Fig. 4 is a front elevation of the mounting for the lower end of the key-levers, part of the key-levers being

broken away and part being in section. 55 Fig. 5 is a fragmentary vertical section taken on the line V—V of Fig. 4. Fig. 6 is a rear elevation of one of the mountings for a plurality of the levers removed from the machine. Fig. 7 is a detail side elevation of the carriage and platen. Figs. 8 and 9 are views of the carriage ball-bearing connections; and Fig. 10 is a detail view showing the slotted portion of the carriage main frame member through which the platen shaft passes and which permits the platen and its supplementary carriage frame member to be moved relatively to the main frame member.

While we have shown one form of machine embodying certain features of our invention, the parts of which may be variously made, and while many features necessary for a complete machine are not shown, such features, as for example, the carriage shift, means for line spacing and other features, may be of any desired construction.

The frame 10 may be of any suitable construction and may be of a light steel structure of a form to make the same very strong, or if desired the said frame may be made of such a construction that it may be placed into another frame or casing of cast iron or other material. As shown the frame has the side members 11 connected together at the rear by a bar 12, and at the front by a transversely-extending bar 13, and intermediate the bars 12 and 13 is a plate 14 from the lower end of which projects a guiding member 15 for the key-levers 16. There may be as many key-levers 16 as there are characters, or each key-lever may represent a plurality of characters as is usual in machines of this character, and each lever is adapted to be guided in a slot 17 in the member 15, 80 said levers being arranged in four rows transversely of the machine to form a keyboard or otherwise arranged as desired. The key-levers are ordinarily arranged in groups 85 of four to adapt the supporting means therefor to be more readily manufactured, and each key-lever has a finger part or key 18 arranged on the outer end 19. The key-levers each have an upwardly-extending part 20, and a downwardly-extending part 105 21 formed integral with the part 19 so as to make each key-lever at the inner part thereof substantially T-shaped in form.

The part or stem portion 21 of each lever is pivoted at 22 within a slot 23 of a bracket 24, which bracket is secured to the plate 25 extending transversely of the machine, and the upper end of each part 20 of the key-levers may be bent, as at 26, and is provided with a pin 27 adapted to move in a slot at 28 at the inner end of the type-bar 29 adjacent to pivot 29^a. The part 20 of each key-lever forms a connecting means between the key-lever and the type-bar, and the part 21 of each lever forms a pivoting portion for each lever and by having each lever constructed in the manner shown, the entire key-lever and connection with the type-bar is made of a single piece and is much better and a more effective movement is thereby provided, which is less likely to get out of order than is the case with the usual link employed to connect the key-levers at their inner ends to the type-bar.

The key-levers 19 through the pins 27 and slots 28 of the type-bars cause the type-bars to be positively moved, and by reason of the pins 27 being normally farther away from the pivoting point 29^a of the type-bars, the said bars will move slowly at first and as the pins approach nearer the pivoting point, the said type-bars will be given a much quicker movement, thus saving much time and permitting the bars to be more rapidly operated without suddenly starting and stopping said type-bars during their greatest speed.

Each key-lever is pivoted at 22 in the blocks or brackets 24, and these blocks are arranged in staggered relation and are each adapted to hold four key-levers. The key-levers, in the form of machine shown, are arranged in four rows and each type-bar may have its head provided with three characters. As shown the blocks or brackets 24 have the slotted portions 23 somewhat extended to provide proper guiding means for the inner end of the key-levers 19, and arranged in an opening 30 is a spring 31, Figs. 5 and 6, one for each key-lever, which normally forces the outer end of the finger part 18 upwardly to return the same to its normal position, the tension of each spring being varied by a screw 30^a. These springs may be arranged in any desired way, and by providing the blocks or brackets 24 in the manner shown and in a staggered relation, the said levers are properly guided in the blocks or supporting brackets and said brackets may be readily made and placed in position in the machine.

Instead of the type striking against the usual cylindrical platen, the type may engage a flat surface, as 31^a, formed as a part of a plate 31^b which extends transversely of the machine and is movable with the carriage 32, the said carriage having a supplementary frame member 32^a and a main

frame member 32^b to the former of which the plate 31^b is secured. The plate 31^b forms the platen Fig. 2, and may be curved for a greater part of its width except at the straight part 31^a, forming the printing point, and said plate may be secured to the part 34 of the carriage frame member 32^a or otherwise held as desired in a position so that the paper or work may be readily passed about the same, though instead of the type striking directly against a metal surface, a yielding surface or strip 35 may be provided and which strip may be so attached that it may be readily replaced in case of wear. A bar 36, Figs. 1 and 2, extends transversely of the machine to the rear of the fixed platen 31^b, and to the bar may be held the work-engaging fingers 37 which may be adjustable along the bar 36 by means of the screws 38. By this means the work may be properly guided about the platen 31^b so as not to interfere with the type and cause the same to make two impressions where a plurality of characters are formed on the type head, as the work immediately on leaving the printing point is made to bend over the surface of the curved platen, and further the various type characters are not required to be curved to correspond to the curvature of the usual cylinder, forming the platen, as is the case with machines of this character.

A roll 39 corresponding to the usual platen roll may be journaled in the frame member 32^a of the carriage 32, and may be provided with finger pieces 40 by which the roll may be rotated, the said finger pieces 40 being secured to the shaft of the roll 39, and to permit the roll and platen frame to move vertically the ends of the main carriage frame member 32^b are slotted where the shaft passes through said member. At the rear of the roll 39 is a second smaller roll 41, which normally engages the roll 39, and at the front of said roll 39 is a still smaller roll 42. The shaft 43 of the roll 41 is held in slots 44 in the frame member 32^a and has peripheral grooves at the ends thereof, and held to the ends of the shaft in such a way as to permit the shaft to rotate are the springs 45 which have one end connected to levers 46. These levers 46, Fig. 7, are pivoted at 47, and have their inner ends, as 48, adapted to be engaged by screws 49, so that the tension of the springs 45 may be varied and the roll 41 yieldingly held against the larger feed roll 39. The roll 42 is similarly held to the roll 39, and has the ends of its shaft 50 held to slide and rotate in the slots 51 of the carriage frame member 32^a, and connected to said shaft are the springs 52 which are connected to the levers 53, the latter being pivoted at 54 and normally forced in one direction by screws 55, to vary the tension of said springs.

Any suitable escapement mechanism may

be provided to operate the carriage for letter spacing, and said mechanism may be variously arranged. In the construction shown, the carriage is provided with a rack-bar 56 which is rigidly held to said carriage, and engaging the teeth of said rack-bar is a pinion or gear 57 and a larger gear 58, Figs. 2 and 3. The larger gear 58, carries a drum portion 59 and in the drum 59 is a spring 60, one end of which is secured to the drum and the other end to a collar on the shaft 61, so that the tendency of said spring 60 and gear 58 is to force the rack-bar 56 and carriage across the machine. The escapement mechanism, including the feed drum 58, is mounted on two plates 62 and 63, forming an escapement frame, which is held to the machine frame in any desired way, and the shaft 61 of the carriage feed is suitably supported in said frame plates or members. A toothed or ratchet wheel 64 is secured to the outer end of the shaft 61, and said ratchet wheel may be provided with handles 65 whereby the latter may be rotated to vary the tension of the spring 60, and engaging the teeth of the wheel 64 to adapt the same to be normally held against rotary movement is a device 66. This device 66 is provided with the pawls 67 and 68, and with a handle portion 69, so that by moving the handle portion 69, the wheel 64 may be permitted to move with a step-by-step movement to release the tension of the spring 60. The shaft 70 of the escapement pinion is rotatably held in the members 62 and 63 of the escapement frame, and on the outer end of said shaft or spindle is a ratchet or escapement wheel 71. This wheel is supported between the frame plate 63 and the bracket 72 and the teeth thereof are adapted to be engaged by a fixed pawl or dog 73 carried by a bell-crank lever 74, the said lever being normally forced in one direction by a spring 75 and having its movement away from the teeth of the wheel 71 limited by a stop 76. The lever 74 is pivoted at 77 to the escapement frame, and has a horizontally-extending portion 78 to which is pivoted the pawl 79. The pawl 79 normally engages the teeth of the wheel 71, and has its upwardly-extending part 80, above its pivot 81, connected to a spring 82, and said pawl has its lower end confined in its swinging movement by a stop or pin 83, carried by the lever 74, and an adjustable stop, as a screw 84, projecting outward from said lever 74. When the outer end, as 85, of the lever 84 is raised, it will release the pawl 79 from the tooth of the wheel 71 and the fixed pawl 73 will directly enter and engage one of the teeth of the wheel 71 to permit the latter to move the distance of one tooth, and said lever 74 will then be restored to its former position to cause the pawl 79 to engage the next tooth of said wheel 71, thus a step-by-step

movement may be imparted to the carriage for letter spacing. It will be seen that the escapement mechanism proper is entirely distinct from the carriage propelling mechanism and that the tendency of the propelling mechanism is normally to force the carriage in one direction, while the escapement simply serves to limit and determine the movement of the carriage, the propelling mechanism being made to directly engage the carriage through the drum gear 58.

The bell crank or angular lever 74 is connected to operate with each movement of the key-levers or spacing bar. To effect this a rod 86 is connected at one end to the lever 74, and this rod at its lower end is connected to an arm 87 extending outwardly from the universal bar 88. The universal bar may be moved in one direction by a spring 88^a and is held to rock between the side members of the machine frame. The universal bar has a transversely-extending bar or part 89 at the lower part thereof and is provided with upwardly-extending parts 90 which are connected under the type-bars 29 by a transversely-extending curved bar or member 91. The type-bars 29 and the bracket or brackets supporting the same are arranged in a curved or semicircular path as is usual, and the transversely-extending bar 91 is adapted to be engaged by the upper end 20 of each of the key-levers, or the spacing bar, as each is depressed, so that the said universal bar may be made to raise the rod 86 and thereby move the lever 74 to permit the escapement to allow the gear 58 to force the carriage one space.

The platen may be raised or lowered to different degrees according to the number of characters or type on the type-bars 29. If there are three characters there should be two shift keys and if only two characters only one shift key is necessary. In the form shown only one shift key is provided for the purpose of illustrating how the platen may be raised. The shift key-lever 92 is held to a transversely-extending rod or shaft 93, and its inner end is pivotally connected at 94 to the vertically-extending bars 95, the latter being connected to move in unison and may be braced by means of the rod 96. One of the bars 95 may be provided with a projection 97 which is limited in its movement by means of the screws 98 arranged at the upper and lower portion of a bracket 99 secured to one of the side members of the frame. The upper end of the bars 95 may be secured to a transversely-extending bar 100 which is adapted to move vertically with the platen and its frame member 32^a, as the platen and paper feed in this instance moves vertically and not the entire carriage. As before stated only one shift key-lever is shown, but two may be provided which are adapted to move the platen and to lock the

same in its adjusted position to adapt the same for the upper case letters and figures.

To properly support the carriage and the platen and paper feed, and to compensate for wear, we may provide a ball-bearing connection between the carriage and the machine frame or parts thereof, to adapt the carriage and platen to move readily across the machine. Adjacent to the bar 100 is a normally fixed bar 101 extending transversely of the machine in which may be arranged screws to serve as guides for the vertically movable bar 100, and extending between the side members of the carriage frame member 32^a is a brace bar 102. A bearing bar 103 is arranged directly over the bearing bar 100, and said bearing bar 103 may move vertically between the pins 104 projecting inward from the side members or ends of the carriage frame member 32^a. The pins serve to guide the bar 103 in its vertical movement with the platen, and interposed between the bearing bars 103 and 100 are balls or bearing members 105. These bearing members may be two in number, and may be connected by a wire 106 to move in unison, and extending upward from the bar 100 may be one or more brackets 107, the upper end of which may be bent at an angle to extend over the upper surface of the bar 103. The bar 101 is fixed to the machine frame while the bar 102 is fixed to the carriage, and the bearing bars 100 and 103 are both movable vertically with the platen frame member 32^a independent of the carriage frame member 32^b, though only the bar 103 moves transversely with said carriage frame members.

A second bearing 108 is provided. This bearing comprises a plurality of bars or members 109, 110 and 111. The intermediate bar or bearing member 110 is fixed to the main frame, and the upper surface of said bar as well as the lower surface of bar 111 are each provided with a V-shaped groove in which the bearing balls or members 112 are supported, and under the bar 110 are the bearing balls or members 113, the said bars being sufficiently spaced apart to permit the said balls to be properly supported between the same. The balls 112 and 113 may be connected in pairs by a wire or connection 114, Figs. 1, 8 and 9, and these wires have their outer ends bent to form a loop for the balls and to space the latter properly apart. Held to the wires or connections 114 are the clips 115 which are adapted to fit about the bar 110 to permit the balls to move in unison and to be properly adjusted, and to be moved lengthwise of the carriage in case the same should become displaced during the movement of the carriage or for any other reason. The lower bar 109 has two brackets 116 extending upwardly therefrom at or near the ends there-

of, and said brackets each have one end formed at an angle and provided with a screw 117 which is adapted to engage the upper surface of the bar 111 so as to force the upper and lower bars toward each other to compensate for any wear that might occur through the ball-bearing connection. The bearing as shown provides an effective means for permitting the carriage to be shifted along its support, and to hold the same substantially rigid and free of all lost motion.

The claims of this application are limited to carriages while the feed mechanism is claimed in our pending application Sr. No. 500,698, filed June 7, 1909; the keyboard in our application Sr. No. 500,694, filed June 7, 1909; the platen in our application Sr. No. 500,695, filed June 7, 1909; the paper feed in our application Sr. N. 500,696, filed June 7, 1909; and other features in other copending applications filed by us.

From the foregoing, it will be seen that a simple and efficient carriage is provided in which the platen has a shift movement in a frame provided therefor entirely independent of the rest of the carriage, and the said carriage and other mechanism so constructed and arranged that the machine is adapted for visible writing; and that simple and efficient bearings are provided for the carriage whereby the carriage is properly sustained and supported in its movement along its support.

Having thus described our invention, we claim as new and desire to secure by Letters Patent:—

1. In a typewriting machine, the combination with a support, of a carriage, and a bearing comprising a plurality of vertically disposed bars extending lengthwise of the carriage, the upper and lower of said bars being movable with the carriage, means for holding the intermediate bar to the support, brackets carried by the lower bar and extending upward over the upper bar, and screws carried by the brackets adapted to engage the upper bar and force said bar and the lower bar toward the intermediate bar.

2. In a typewriting machine, the combination with a support, of a carriage, and a bearing comprising a plurality of vertically disposed bars extending lengthwise of the carriage, the upper and lower of said bars being movable with the carriage, means for holding the intermediate bar to the support, brackets carried by the lower bar and extending upward over the upper bar, and means carried by the brackets adapted to engage the upper bar and force the bars toward each other.

3. In a typewriting machine, the combination with a support, of a carriage mounted on said support, a bearing bar held to said support, a plurality of balls arranged above

- and below said bar, wire connections between the balls holding the same properly spaced apart in pairs, clips secured to the wire connections and fitting about said bar 5 to permit adjustment of the balls, and bearing bars movable with the carriage on opposite sides of the first-mentioned bar.
4. In a typewriting machine, the combination with a support of a carriage mounted 10 on said support, a plurality of balls, independent means holding the balls properly spaced apart in pairs, bars between which the balls move, clips secured to the ball holding means and fitting about one of said 15 bars to permit adjustment of the balls.
5. In a typewriting machine, the combination with a support, of a carriage, and a bearing comprising a plurality of vertically disposed bars extending lengthwise of the 20 carriage, the upper and lower of said bars being movable with the carriage, means for holding the intermediate bar to the support, brackets carried by the lower bar and extending upward over the upper bar, means 25 carried by the brackets adapted to engage the upper bar and force the bars toward
- each other, and an independent bearing having a relative movement with respect to the first mentioned bearing, substantially as and for the purpose set forth. 30
6. In a typewriting machine, the combination of a support, a carriage and a bearing comprising a normally fixed bar having a channel on one side thereof, a bar located above the fixed bar and having a channel on the under surface thereof opposed to the first mentioned channel to form a raceway, a second bar located under the fixed bar and mounted to move with the carriage and spaced from said fixed bar to provide a raceway, a plurality of balls, independent means holding the balls properly spaced apart in pairs in said raceways, clips secured to the ball holding means and fitting about the fixed bar to permit adjustment of the balls. 35 40 45
